Primary Examiner—Alan P. Douglas*Assistant Examiner*—Monica A. Hannon*Attorney, Agent, or Firm*—Kinney & Lange[57] **CLAIM**

The ornamental design for a wall mounted infant seat, as shown and described.

DESCRIPTION

FIG. 1 is a front perspective view of a wall mounted infant seat showing our new design;

FIG. 2 is a right side elevational view, the left side being a mirror image thereof;

FIG. 3 is a top plan view thereof;

FIG. 4 is a bottom plan view thereof;

FIG. 5 is a front elevational view thereof;

FIG. 6 is a rear elevational view thereof; and,

FIG. 7 is a front perspective view, in a closed position thereof.
